ABSTRACT

A jack particularly suited for lifting roll loads has means for pivoting a first arm about an end of the arm pivoted on a support. A load lifting side of the first arm ends in a hook at a free end of the arm. The hook retains the load on the arm for lifting the load by pivoting the arm. A second arm has a retaining hook at a free end of the arm which end is positioned intermediate the ends of the first arm. The second arm is pivoted on the first arm for moving the hook of the second arm above or below the lifting side of the first arm. Means operable for retaining the hooked end of the second arm above the lifting side of the first arm are provided. The hook of the second arm then retains the load to effectively shorten the lifting arm of the jack.

ROLL JACKS

BACKGROUND OF THE INVENTION

This invention relates to a jack for lifting loads. From ancient times to the present, man has devised a wide variety of devices for lifting an even wider variety of articles. These lifting devices or jacks are often particularly adapted to the articles to be lifted. For example, one would expect a house jack to be different from a device for lifting eggs. The extent of lifting required also affects the design of such devices. For example, one would expect an oil well rig to be different from a drill press.

One article of present industrial utility which presents its own unique lifting problem is large rolls of paper, wire or a variety of other products. Such rolls are made about a shaft or hub without a rim extending beyond the circumference of the roll. With such rolls, the amount of material comprising the roll determines the diameter of the roll. A roll which has been partially used or simply manufactured in a different quantity from another roll of like material then has a different diameter.

Rolls of material are used in a variety of industrial operations. One example is the use of large rolls of pasteboard in the manufacture of pasteboard boxes. Such rolls are often mounted in machines for utilizing the material of the roll by unwinding the material from the roll. When one roll is completely unwound, it is replaced by a full roll. The full roll must be lifted into the machine. Since the rolls may vary in size, the machine cannot be constructed to readily receive a succession of such rolls without lifting the rolls. Moreover, the rolls are conveniently moved from one place to another by rolling them on their circumferences. In such practice, the rolls are not accompanied by devices for placing the roll in the machine.

When the roll is supported on its circumference, the center of the roll will vary in height from the surface supporting the roll according to the radius of the roll. Of course, the radius of the roll depends upon the amount of material comprising the roll, the more material the greater the radius. Rolls of more material will also weigh more than rolls of less material to present a greater weight to be lifted into the machine. A device suitable for lifting such rolls into a machine must be able to lift the largest such roll to be presented to the machine. As a general rule, the more powerful a lifting device, the greater its cost. Accordingly, each machine utilizing a roll of material and having a device for lifting the roll into the machine has required an expensive lifting device suitable for lifting the heaviest roll to be presented to the machine.

SUMMARY OF THE INVENTION

It is therefore an object of the invention to provide a jack particularly suited for lifting large, heavy rolls of material into the machine and readily adaptable to lift smaller, lighter rolls of material into the machine.

The invention provides a jack constructed to take advantage of the relationship between the radius and the weight of a roll of material to be particularly suited for lifting such roll loads. This jack has a first arm pivoted at one end on a support and having a load retaining hook at the other, free end. Means for pivotally moving the first arm are provided. A second arm also having a

2
retaining hook at a free end positioned intermediate ends of the first arm is pivoted on the first arm for moving the hook of the second arm above or below a lifting side of the first arm which side ends in the hook of the first arm. Means operable for retaining the second arm in a position with its hooked end raised above the lifting side of the first arm are provided. The hook of the second arm then engages the load to effectively shorten the lifting arm of the jack.

DESCRIPTION OF THE DRAWINGS

A preferred embodiment which is intended to illustrate and not to limit the invention will now be described with reference to drawings of the embodiment, 15 in which:

FIG. 1 is a perspective view of the embodiment showing lifting movement of the arms;

FIG. 2 is a side view of the embodiment shown in FIG. 1 with certain parts in a different position; and

FIG. 3 is a side view of the embodiment shown in FIG. 1 with a second arm in a raised position.

DESCRIPTION OF THE PREFERRED EMBODIMENT

25 FIG. 1 shows a roll 10 of material having an axle 12 extending from an end of the roll along the axis of rolling of the material of the roll. The roll is to be placed on a portion 14 of a machine for utilizing the material of the roll. A jack generally at 16 has an arm 18 pivoted at one end on a support 20 and having a hook 22 at an opposite, free end. A roll lifting side 24 of the arm faces the axle of the roll and ends at the hook 22. A piston and cylinder 26 are operatively connected to the arm 18 for rotating the arm about its pivot. Such rotation of 30 the arm engages the lifting side of the arm with the axle of the roll. Continued rotation of the arm lifts the axle to lift the roll. Of course, a jack similar to that generally at 16 may be disposed at an end of the roll opposite that shown for uniformly lifting the roll.

40 A second arm 28 is pivotally connected to the first arm at one end with a hook 30 at an opposite, free end of the second arm intermediate ends of the first arm. A removable pin 32 extends from the first arm adjacent the second arm. With the pin 32 removed from the first arm, the second arm may be pivoted to dispose the hook 30 of the second arm above the lifting side 24 of the first arm. The pin 32 is then returned to the first arm to be operable to retain the hook 30 above the lifting side of the first arm. The hook of the second arm can then engage a shaft of a large roll after which pivoting of the first arm will lift the roll.

45 The axle 12 has teeth on a pinion portion 34 positioned to engage cooperative teeth of a rack 36 on the machine portion 14. A similar rack and pinion portion at an opposite end of the roll, not shown, cooperates with the pinion portion and rack 34 and 36 to control 50 rolling movement of the roll along the machine portion 14. The teeth of the cooperative pinion portions and racks prevent slippage of the pinion relative to the rack which would turn the rack toward or away from the machine portion 14. With the cooperative engagement of the pinion portion and rack, the roll 10 can then be moved parallel to the machine portion 14 for proper mounting in the machine.

55 The axle 12 has a further portion 38 extending from the pinion portion away from the roll. The portion 38 is of reduced diameter relative to the pinion portion to 60

65 The axle 12 has a further portion 38 extending from the pinion portion away from the roll. The portion 38 is of reduced diameter relative to the pinion portion to

provide a positioning shoulder 40 at the transition from the axle portion 34 to portion 38. The shoulder 40 and a similar shoulder on an axle at an opposite end of the roll, not shown, are spaced relative to the arm 18 and a similar arm of another jack adjacent the opposite end of the roll, not shown, to closely pass along a side of the arm 18 as the roll is moved along the arm toward the machine. If the roll tends to rotate about an axis normal to the path of movement, a leading or trailing portion of the shoulder 40 relative to the direction of movement will then engage the adjacent side of the arm 18 to provide a resistance to further rotation of the roll. The spacing of the shoulder 40 from the adjacent side of the arm 18 is such that the rotation of the roll permitted by the shoulder is less than the distance between adjacent teeth on the rack over the width of the rack. In this way, proper positioning of the roll and meshing engagement of the pinion portion 34 and rack 36 are assured. Movement of the roll from the supporting surface to the machine is thus constrained to straight line entry movement of the roll into the machine.

FIG. 2 shows the roll 10 in a position lifted by the arm 18 and, in phantom, supported on a surface before engagement with the arm 18. Looking first at the phantom, pre-engagement position of the roll and arm, it is seen that the point of engagement between the axle 12 and the arm 18 will be below the hook 30 of the second arm considered relative to the first arm from the pivot toward the roll supporting surface. Such a roll is here considered a small roll having a corresponding small weight.

Fluid pressure is then supplied to an inlet port 42 of piston and cylinder 26 to drive the piston, not shown, downward to the position shown in FIG. 2. Another port 44 of the piston and cylinder is vented. The piston and cylinder is mounted on the support by a pivot 46. A piston rod 50 connected to the piston at one end is pivotally connected to a lever 52 at its other end. The lever 52 is fixedly connected to a shaft 54 which is also fixedly connected to the arm 18. The shaft 54 is mounted for rotation in the support. Movement of the piston then draws the connected piston rod, lever 52, shaft 54 and arm 18 into the position shown in FIG. 2.

As the arm 18 moves from the position shown in phantom to the other position shown in FIG. 2, the lifting side 24 of the arm 18 engages the axle 12. The axle is first pushed away from the support until the hook 22 at the free end of the lifting side 24 engages the axle. The axle is then held on the arm to be arcuately lifted by continued movement of the arm 18.

The arm 18 is fixed to the shaft 54 relative to the stroke of the piston of the piston and cylinder 26 such that the arm will be substantially parallel to the rack 36 for transferring the axle from the arm to the rack at one end of the stroke. In an alternative embodiment of the invention the lifting side 24 of the arm may be inclined slightly downward from the hook 22 toward the rack 36 to facilitate rolling the roll from the arm onto the rack. In another alternative embodiment, the lifting side of the arm 18 may decline slightly from the rack 36 toward the hook 22 to retain the roll at the hook under gravity until it is desired to push the roll uphill to the rack 36. The angle of decline from the rack 36 to the hook 22 is less than the angle of decline when the arm 18 first engages the roll when the roll has been lifted from the supporting surface by the arm.

FIG. 3 shows a roll 10' larger than the roll 10. An axle 12' of the roll 10' similar to the axle 12 is now presented to the arm 18 intermediate the hook 30 of the second arm and the shaft 54 when the roll 10' is supported on the roll supporting surface. Because the roll 10' is larger than the roll 10, it is heavier than the roll 10. If the jack were then to operate as described with reference to FIG. 2, the axle 12' would be lifted while engaged with the hook 22 of the arm 18. The weight of the roll 10' must then be supported over the entire length of the arm 18. The power required of the cylinder is determined by the relative length of arm 18 from the shaft 54 to the hook 22 relative to the arm 52 from the shaft 54 to its pivotal connection to the piston rod 50. The power required is thus relatively greater for the heavier roll 10'.

However, FIG. 3 shows the second arm pivoted above the lifting side 24 of the arm 18 and retained there by the pin 32 under an opposite side of the second arm from that which engages the axle. When the piston and cylinder 26 now swings the arm 18, the roll is pushed along the second arm until it engages the hook 30 of the second arm. Continued movement of the arms then lifts the roll 10'. Now, however, the relative power required in the piston and cylinder 26 is determined by the relative length of the combination of first and second arms from the roll retaining hook 30 of the second arm to the shaft 54 compared with the length of the arm 52 from the shaft 54 to its connection to the piston rod 50. Since the hook 30 is intermediate ends of the arm 18, the distance from the hook 30 to the shaft 54 is less than that from the hook 22 to the shaft. Accordingly, the power required in the piston and cylinder is less. Similarly, the arm 18 need only lie strong enough to support the roll 10' at the hook 30, not at the hook 22.

As described in relation to the arm 18 with reference to FIG. 2, the relative position of the second arm may, in alternative embodiments, assume angles relative to the rack 36 either urging the roll toward the rack or retaining the roll at the hook.

In considering the purpose of the jack for lifting a roll for introduction to a machine, it is clear that a single arm is undesirable because a relatively long arm 18 would be required to reach the relatively low axles of small rolls while, at the same time, requiring relatively greater power of the piston and cylinder 26 and strength of the arm 18 when lifting larger rolls.

Further consideration of the purpose of the jack will clearly indicate that a detent in the side 24 suitable for hooking an axle should it engage the side above the detent would be unsuitable as the axle would then have to be lifted from the detent before it could be moved onto the rack 36. If the roll has to be otherwise lifted, the jack has failed in its purpose. Still further consideration of the purpose of the jack will indicate that a second hook permanently interposed on the side 24 between the hook 22 and the rack 36 is also unsuitable. In this latter arrangement, the roll would have to be lifted over the second hook and the lifting of the roll again defeats the purpose of the jack. Even if the portion of the second hook extending toward the hook 22 were inclined toward the side 24 so that the roll 12 could be rolled up the incline past the second hook, the roll would then fall from the top of the second hook to the roll supporting side 24. The impact of such a drop would again require a stronger arm 18 than the present

jack and further presents danger of breaking the axle 12 or otherwise dropping the roll.

Having thus described my invention, what I claim as new and desire to secure by letters Patent of the United States is:

1. A jack, comprising: a first arm pivoted at one end on a support and having a load retaining hook at the other, free end; means for pivoting the first arm relative to the support; a second arm having a load retaining hook at a free end positioned intermediate ends of the first arm and connected to the first arm at the other end for pivotal movement of the hook of the second arm above a load lifting side of the first arm, which side of the first arm ends in the hook of the first arm; and

means operable for retaining the hooked end of the second arm above the lifting side of the first arm.

2. A jack as in claim 1 wherein the means for moving the arm are a fluid operated piston and cylinder.

3. A jack as in claim 1 wherein the means operable for retaining the second arm in the raised position is a pin removably extending from the first arm.

4. A pair of jacks as in claim 1 each engaging an axle extending from opposite ends of the load, the axle having shoulders spaced to closely pass along sides of the first arm of each jack for positioning the axle between the jacks.
